PROCESS OF MAKING CUTTING
BLOWPIPE TIPS

Lorn Campbell, Jr., Lakewood, Ohio

Application February 13, 1931, Serial No. 515,524

2 Claims. (Cl. 29—157)

This invention relates to a process of making cutting tips for blowpipes, and has for its general object to produce a tip which will be particularly efficient in operation and especially useful in operating with fuel gas under low pressure (from 5 four to six ounces per square inch).

As is well known in the art of cutting metal with blowpipes, it is necessary that the passages for the preheating mixture shall converge toward 10 the operating end of the tip in such manner that the preheating flames shall impinge upon a small area only of the metal, in order to insure quick preheating of the metal and to enable the cutting operation to be initiated with corresponding 15 quickness or rapidity.

It has been customary heretofore, in fabricating cutting tips, to provide the central oxygen bore and the surrounding bores for the preheating mixture by drilling larger passages from the 20 upper end of the tip body to the upper end of the tapered or frusto-conical operating end of the body and then to drill smaller passages from the operating end of the tip body to intersect the lower ends of the corresponding larger passages. 25 It has been found very difficult to obtain accurate registration of the junctions of the smaller and larger passages; and this lack of accurate registration at the junctions will result in irregularities 30 in the character of the preheating flames. If one of them fails to register with the others, the metal will be preheated unequally and inefficiently, with a resultant lack of efficiency in the operation of the tip and a corresponding increase in the con- 35 sumption of tank oxygen.

In order to overcome these objections, I have 40 constructed tips for cutting blowpipes in the manner described hereinafter and illustrated in the accompanying drawing, wherein Fig. 1 represents a side elevation of a tip for a cutting blowpipe; Fig. 2 a bottom plan view and Fig. 3 a top plan view of the said tip; Fig. 4 a central longitudinal sectional view through the blank from which the said tip is made, the said blank 45 having a central passage for cutting oxygen and passages for preheating mixture grouped about such central passage; Fig. 5 a view similar to Fig. 4, showing mandrels or wires inserted into the passages; Fig. 6 a view similar to Figs. 4 and 50 5 showing the final external shape given to the tip body, and also showing the mandrels or wires in place; and Fig. 7 a view similar to Fig. 6, showing the finished tip with the wires or mandrels 55 removed.

55 In the production of a tip made in accordance

with my invention, I prefer to employ a blank of pure electrolytic copper, which possesses great heat radiating properties and which, because of its high conductivity, carries the reflected heat of the intense flame (having a temperature of 6300° 5 F.) away from the operating ends of the tips and dissipates and radiates it into the air, thereby prolonging the lives of the tips. The purer the copper employed, the greater its conductivity; but, incidentally, the more difficult is the machining, because such pure copper is very hard on 10 machine tools and very difficult to work, because of its tenacity.

By my process of fabricating the tips, it is possible to use the purest copper and to make the 15 bores continuous and without irregularities throughout their entire length, which irregularities produce the objectionable results referred to hereinbefore.

Referring to the drawing, 1 denotes a cylindrical blank of proper diameter and length for a blowpipe tip, the blank being shown as provided at its upper end with a cylindrical enlargement 2 by means of which it may be secured, as by a shouldered nut, to the front or lower end of the 20 blowpipe head. This blank is provided with a central bore 3 for cutting oxygen, the said bore being of uniform diameter throughout the length of the blank and with smaller bores 4 grouped about the central bore and extending the full 25 length of the blank and parallel with the central bore and with each other and also being of the same diameter throughout their respective lengths. At their upper ends the bores 4 are shown as merging with an annular recess 5, such 30 as is commonly provided for the distribution to said bores of the preheating mixture from the appropriate passage or passages in the head. Inserted in the bores 3 and 4 are mandrels 6 and 7, 35 the said mandrels being of the diameter desired for the delivery or operative ends of the bores within which they are respectively inserted, it being noted that the mandrel 6 is of somewhat 40 greater cross sectional area than the mandrels 5. 45

The mandrels having been thus inserted, the lower or operative end of the tip is shaped, as by swaging, so as to give it the frusto-conical form indicated at 8, the lower or operative ends of the bores 3 and 4 being thereby reduced in cross sectional area to an extent determined by the engagement of the walls of the bores with the mandrels.

As will be evident from an inspection of Figs. 6 and 7, the reduced lower or operative ends 3a and 4a of the bores 3 and 4 respectively merge smooth- 50 55

ly and uninterruptedly with the main or larger portions of said bores. Heretofore, the junctions of the reduced and smaller portions of these bores have produced irregularities in the bores at such junctions, and these irregularities have in turn resulted in the production of flames of unequal length issuing from the preheating jets, with the consequent inefficiency in the preheating operation pointed out hereinbefore.

10 A blowpipe tip constructed in accordance with my invention will produce a more concentrated and intense preheating flame than is ordinarily obtainable from tips constructed in accordance with former practices, and the preheating flames produced are less harsh and blowy than those produced by such other tips.

Where the fuel gas which is employed is acetylene, equal parts of acetylene and oxygen under high pressure from the tip are supplied through the preheating passages, the combustion of the acetylene being completed by oxygen admitted to the deoxidized zone within the preheating flames. In the case of a harsh or blowy flame, the molten metal is agitated and atmospheric oxygen is conveyed into the zone which should be enclosed by the burning preheating jets at their contact with the metal and which zone should be deoxidized by the chemical reaction of the flame. Where the atmospheric oxygen breaks into this zone, it not only results in inefficiency in the cutting operation itself, but necessitates the use of more tank oxygen for the production of the preheating mixture. By producing a blowpipe tip having passages free from irregularities, I am enabled to overcome the objections noted hereinbefore; and, as pointed out, a tip having such smooth and unobstructed passages is particularly effective for the use of low-pressure combustible gas. Furthermore, by swaging the operating end of the tip, the metal is condensed and compacted and its conductivity is thereby increased, enabling the intense heat to which this end of the tip is subjected to be conducted quickly to the body of the tip and to be radiated therefrom, with a corresponding increase in the life of the tip.

Having thus described my invention, what I claim is:

1. The process of making a unitary blowpipe tip having a central bore for cutting oxygen and a plurality of bores for preheating mixture grouped about such central bore, said process consisting in providing a blank of ductile metal; forming in one end of said blank an annular recess; providing said blank with a central bore

for cutting oxygen extending longitudinally therethrough and with a plurality of bores for preheating mixture extending longitudinally therethrough and grouped about the central bore and substantially parallel therewith and communicating each at one end with said recess; inserting into said bore cylindrical mandrels of smaller diameters than the diameters of said bores; and subjecting the end of said blank which is opposite the one provided with the annular recess to pressure in such manner that the said end is given a substantially frusto-conical shape, the delivery portions of all of said bores are brought into engagement with the corresponding portions of said mandrels therein, and the delivery end portions of the bores for preheating mixture are reduced in diameter and are inclined toward the reduced delivery end of the central bore and the delivery end portion of each bore for preheating mixture merges smoothly with the enlarged portion of such bore which is remote from the delivery end of the tip.

2. The process of making a unitary blowpipe tip having a central bore for cutting oxygen and a plurality of bores for preheating mixture grouped about such central bore, said process consisting in providing a blank of ductile metal; forming in one end of said blank an annular recess; providing said blank with a central bore for cutting oxygen of substantially uniform diameter throughout its length and extending longitudinally therethrough and with a plurality of bores for preheating mixture extending longitudinally therethrough and grouped about the central bore and substantially parallel therewith and communicating each at one end with said recess and each being of substantially uniform diameter throughout its length; inserting into said bore cylindrical mandrels of smaller diameters than the diameters of said bores; and subjecting the end of said blank which is opposite the one provided with the annular recess to pressure in such manner that the said end is given a substantially frusto-conical shape, the delivery portions of all of said bores are brought into engagement with the corresponding portions of said mandrels therein, and the delivery end portions of the bores for preheating mixture are reduced in diameter and are inclined toward the reduced delivery end of the central bore and the delivery end portion of each bore for preheating mixture merges smoothly with the enlarged portion of such bore which is remote from the delivery end of the tip.
